UNITED STATES PATENT OFFICE.

OSCAR L. LAWSON AND JAMES H. REED, OF LYNN, MASSACHUSETTS.

THREAD-MEASURING DEVICE FOR SEWING-MACHINES.

1,245,935.

Specification of Letters Patent.

Patented Nov. 6, 1917.

Application filed March 24, 1915. Serial No. 16,767.

To all whom it may concern:

Be it known that we, OSCAR L. LAWSON, a subject of the King of Sweden, and JAMES H. REED, a citizen of the United States, residing at Lynn, county of Essex, State of Massachusetts, have invented a certain new and useful Improvement in Thread-Measuring Devices for Sewing-Machines, of which the following is a specification, reference being had therein to the accompanying drawings.

Our present invention has to do with the thread measuring mechanism and the thread lock for sewing machines of the type shown in the prior application of Oscar L. Lawson, filed August 27, 1914, Ser. No. 858,825 which eventuated into Pat. No. 1,217,871, Feb. 27, 1917. In that application there is shown a thread measuring and locking mechanism which is controlled by the position of the presser foot so that a proper length of thread for the formation of the stitch is fed in spite of variations in the thickness of the stock which is being operated upon. The present invention affords a positively operated mechanism for accomplishing this purpose and does away with the employment of springs so that the operation of the device is more certain and efficient than that shown in the application previously referred to. This makes it possible to run the machine at a high rate of speed without diminishing the effectiveness of the thread measuring and locking mechanism.

The invention will be fully understood from the following description when taken in connection with the accompanying drawings and the novel features thereof will be pointed out and clearly defined in the claims at the close of this specification.

In the drawings, Figure 1 is a side elevation of a machine embodying our invention.

Fig. 2 is a view of the parts shown in the lower part of Fig. 1 said parts being shown in the position which they occupy at the time when the thread measuring arm is lifted.

Fig. 3 is a front elevation of the parts shown in Fig. 2.

Referring to the drawings, and particularly to Fig. 1, there is shown at 11, the presser foot having a tail 12 the whole being pivoted at 13. It will be seen that when the presser foot is raised, either by hand for the insertion of the work, or periodically during the feed of the work, the tail of the presser foot will be correspondingly lowered. Ac-

cordingly there is connected to the tail of the presser foot a connecting rod 14, the position of the lower end of which determines the amount of thread delivered to the stitch forming mechanism. The upper end of the connecting rod is attached to the tail of the presser foot by means of an adjusting screw 15 passing through a thimble 16 in a lug formed on the tail of the presser foot. The other end of the screw engages another lug on the presser foot. The screw threaded portion of the screw 15 passes through a collar 17 to which the connecting rod 14 is pivoted at 18. It will therefore be seen that when the screw 15 is rotated, the collar 17 will be moved toward or away from the pivot 18 about which the presser foot moves, and that the amplitude of movement of the connecting rod 14 will be correspondingly varied.

At 19 is shown a shaft on which is located a cam 20 having a cam groove 21 in which travels a cam roll 22 on one end of a lever 23 pivoted at 24 to the frame of the machine. The rotation of the cam 20 gives a positive motion of uniform amplitude to the lever 23 in time with the other parts of the machine. The front end of the lever 23 is provided with a downwardly extending pin 25 at substantially right angles to the length of the lever 23. This pin 25 passes through a hole 26 in a head 27 pivoted at 28 to the lower end of the connecting rod 14. The hole is countersunk or bored out as shown in dotted lines in Fig. 1 so that the lever 23 is free to swing about its pivot 24 without causing the pin 25 to bind in the hole 26. It will be seen that each time the lever 23 is oscillated by the cam 20 the pin 25 pulls the head 27 to the left as shown in Fig. 1 (see also Fig. 2) an amount depending on the height at which the head 27 is then held by the connecting rod 14.

At 29, is shown a hole similar to the hole 26 and through this hole passes a pin 30 forming one arm of a bell crank lever, the other arm of which is designated 31. This bell crank lever is pivoted at 32 and terminates at its front end in a half round thread measuring arm 33 extending at right angles to the lever 31. Beneath this half round thread engaging member 33, is located a second half round member 34 on an arm 35 also pivoted at 32 to the frame of the machine. For convenience this member may be termed the thread clamp 34. These two half round members 33 and 34 rest upon a fixed pin 36 and the thread clamp 34 is held

in contact with the fixed pin by a spring 37. The lever 35 on which is placed the thread clamp 34 is extended rearwardly as shown at 38 and provided with an adjustable pin 39.

5 The thread *a*, see Fig. 2, to be fed passes from the cop or spool of thread under the thread clamp 34 around the two half round portions and down into the wax-pot not shown, from which it is carried to the stitch forming mechanism. It will be seen that the 10 spring 37 clamps the thread as it comes from the cop firmly but gently between the fixed pin 36 and the thread clamp 34. Each time the cam 20 revolves the movement of the 15 lever 23 pulls the head 27 to the left and lifts up the thread measuring arm 33 a distance depending upon the position vertically of the head 27. The position occupied by these parts at the time when the head 27 20 has been drawn to the left is shown in Fig. 2. As the end of the thread which passes down to the wax pot is at this time held firmly by the work, the upward movement of the thread measuring arm 33 draws a portion 25 of the thread through between the lower thread engaging lever 34 and the fixed pin 36 thus measuring off the proper amount for the formation of the next stitch. The two thread engaging members then close. It will 30 be seen that the extent to which the two thread engaging members 33 and 34 are separated will depend upon the position of the presser foot 11 which will lower the head 27 an amount proportional to the amount which 35 the presser foot is raised by any increase in thickness in the work. The lowering of the head 27 increases the distance from the pivot 24 to the point of contact between the pin 25 and the cross head 27. It also shortens 40 the distance between the cross head 27 and the pivot 32, about which the thread measuring arm moves. Adjustment is easily accomplished by turning the screw 15, thereby changing the ratio between the movement of 45 the presser head and the movement of the cross head 27. The pin 39 is provided so that when the presser foot is lifted up, for the insertion or removal of the work, the cross head 27 will be brought into engagement with the upper end of said pin 39 and will lift up the thread clamp 34 so that it 50 will no longer pinch the thread against the fixed pin 36, and the thread will then be free to be drawn out.

55 The construction just described is positive in its operation and the parts are so constructed that a uniform operation results regardless of the speed at which the machine is run. This is a matter of considerable importance because it has been found in actual 60 practice that there is a tendency of the machines to feed the thread differently at different rates of speed.

What we claim is—

65 1. In combination with a presser foot, an

arm on one end of which said presser foot is mounted, a downwardly extending connecting rod pivotally connected at its upper end with said arm, a cross head pivotally connected with the lower end of said rod, a 70 two armed lever fulcrumed intermediate its ends, one arm of said lever forming a thread measuring arm and the other arm having a loose sliding connection with said cross head, said loose connection permitting movement 75 of the cross head with relation to the fulcrum point of said lever thereby varying the throw of the thread measuring arm, another lever fulcrumed intermediate its ends, one arm of which has a finger which has a loose 80 sliding connection with said cross head, and a cam having operative connection with said other arm of the last mentioned lever whereby the lower end of said connecting rod is oscillated and thereby the thread measuring 85 arm is actuated.

2. In combination with a presser foot, an arm on one end of which said presser foot is mounted, a downwardly extending connecting rod pivotally connected at its upper 90 end with said arm, said presser foot arm being fulcrumed at a point between the presser foot and the pivotal connection of said rod with said arm, a head pivotally connected with the lower end of said rod, a lever fulcrumed intermediate its ends, one arm of said lever forming a thread measuring arm and the other arm being loosely connected with said head, said loose connection permitting movement of the head with relation 95 to the fulcrum point of said lever, thereby varying the throw of the thread measuring arm, another lever fulcrumed intermediate its ends one arm of which has a loose connection with said head, and a cam having 100 operative connection with the other arm of said last mentioned lever whereby said last mentioned lever is given a uniform amplitude of movement on its fulcrum and by its connection with said head oscillates the 105 lower end of said connecting rod and thereby actuates the thread measuring arm. 110

3. In combination with a presser foot, an arm on one end of which said presser foot is mounted, a downwardly extending connecting rod pivotally connected at its upper end with said arm, a cross head pivotally connected with the lower end of said rod, a two armed lever fulcrumed intermediate its ends, one arm of said lever forming a thread 115 measuring arm and the other arm having a loose sliding connection with said cross head, said loose connection permitting movement of the cross head with relation to the fulcrum point of said lever thereby varying the throw of the thread measuring arm, another lever fulcrumed intermediate its ends, one arm of which has a finger which has a loose 120 sliding connection with said cross head, a cam having operative connection 125 with said cross head, a downwardly extending connecting rod pivotally connected at its upper end with said arm, a cross head pivotally connected with the lower end of said rod, a two armed lever fulcrumed intermediate its ends, one arm of said lever forming a thread 130 measuring arm and the other arm having a loose sliding connection with said cross head, a cam having operative connection 135

with said other arm of the last mentioned lever whereby the lower end of said connecting rod is oscillated and thereby the thread measuring arm is actuated, a pivoted thread 5 clamp, and a stop pin connected with said thread clamp which is adapted to be engaged by the cross head in its downward movement when the presser foot is lifted to thereby turn the said thread clamp on its 10 pivot and release the thread.

4. In combination with a presser foot, an arm on one end of which said presser foot is mounted, a downwardly extending connecting rod pivotally connected at its upper 15 end with said arm, a cross head pivotally connected intermediate its ends with the lower end of said rod, a lever fulcrumed intermediate its ends, one arm of said lever forming a thread measuring arm and the

other arm having a loose connection with 20 one end of said cross head in such manner as to permit movement of the head with relation to the fulcrum point of said lever, another lever fulcrumed intermediate its ends, 25 one arm of which has a loose connection with the other end of said cross head in such manner that the cross head is movable with relation to the fulcrum of said mentioned lever and means for oscillating said last mentioned lever on its fulcrum and thereby 30 actuating the thread measuring arm.

In testimony whereof we affix our signatures, in presence of two witnesses.
